(57) **CLAIM**

The ornamental design for a novel sleep button control panel for a remote control, as shown and described.

DESCRIPTION

FIG. 1 is a front planar view of the sleep button control panel for a remote control.

FIG. 2 is an upper front left perspective view of the sleep button control panel for a remote control of FIG. 1.

FIG. 3 is an upper front right perspective view of the sleep button control panel for a remote control of FIG. 1.

FIG. 4 is a lower front left perspective view of the sleep button control panel for a remote control of FIG. 1.

FIG. 5 is a lower front right perspective view of the sleep button control panel for a remote control of FIG. 1.

FIG. 6 is a front left perspective view of the sleep button control panel for a remote control of FIG. 1; and,

FIG. 7 is a front right perspective view of the sleep button control panel for a remote control of FIG. 1.

The broken lines in FIGS. 1-7 are for illustrative purposes and form no part of the claimed design.

1 Claim, 7 Drawing Sheets
